UNITED STATES PATENT OFFICE.

JOSEPH WALKER, OF CANONSBURG, PENNSYLVANIA.

POSTAL CARD.

No. 878,117.

Specification of Letters Patent.

Patented Jan. 7, 1908.

Application filed August 22, 1906. Serial No. 331,565.

To all whom it may concern:

Be it known that I, JOSEPH WALKER, a citizen of the United States of America, residing at Canonsburg, in the county of Washington and State of Pennsylvania, have invented certain new and useful Improvements in Postal Cards, of which the following is a specification, reference being had therein to the accompanying drawing.

10 This invention relates to certain new and useful improvements in postal and mailing cards, and the invention has for its object the provision of novel means for protecting the picture or message side of a card. To this end, I have devised a folding card, which will be extremely simple in construction, light and durable.

20 The detail construction of my improved card will be presently described, illustrated and then specially pointed out in the appended claims.

25 Referring to the drawing forming part of this specification, like numerals of reference designate corresponding parts in the several views of the drawing, in which:—

Figure 1 is a plan of my improved card, Fig. 2 is a similar view of the same partially folded, Fig. 3 is a plan of a folded card, Fig. 4 is a similar view of the reverse or address side 30 of the card; and Fig. 5 is a cross sectional view of the same.

35 My improved postal or mailing card comprises a piece of durable paper or card board 1 having a closure flap 2, which is provided with a tongue 3 having protuberances or tabs 4. The piece of paper or cardboard 1 is adapted to be folded upon the dotted line 5, whereby the picture or message carried by the card will be protected. The folding part 40 6 of the card is provided with a slit or slot 7 adapted to receive the tongue 3 and tabs 4 of the closing flap 2. The reverse side 8 of the card is used for the address.

By the construction of my improved card, the message written thereon or the picture 45 carried thereby will be fully protected while the card is being handled by the postal authorities, and the liability of the authorities reading or observing the card is reduced to a minimum.

Having fully described my invention what I claim is:—

A postal card comprising a body portion terminating in an inclosing and an imperforate retaining flap, said inclosing flap of the 55 same size as and adapted to be folded against the rear face of the body portion and provided with a longitudinal slit at a point intermediate the center thereof and the junction between said flap and body portion, said retaining flap of less width than the body portion, having a curved edge and further provided approximately centrally of its curved edge with a tongue having its free end formed with lateral protuberances, said protuberances further having rounded ends and each of said protuberances further having the edges thereof extending in parallelism with respect to each other, that portion of said tongue extending from the upper edge of the 60 protuberance to its juncture with the retaining flap being of the same width throughout and of a width substantially equal to the length of the said longitudinal slit said retaining flap adapted to be folded against the 65 rear of the inclosing flap and have the tongue thereof extend through said slit so that the protuberances will engage against the inner face of the inclosing flap thereby securing the flaps together.

70 In testimony whereof I affix my signature in the presence of two witnesses.

JOSEPH WALKER.
